UNITED STATES PATENT OFFICE

147,600

DESIGN FOR A THERAPEUTIC LAMP

Albert Simon and Lawrence Rellinger, Detroit,
Mich., assignors to Pacer, Inc., Detroit, Mich.,
a corporation of Michigan

Application January 21, 1946, Serial No. 125,820

Term of patent 7 years

(Cl. D48—20)

To all whom it may concern:

Be it known that we, Albert Simon and Lawrence Rellinger, citizens of the United States of America, residing in the county of Wayne and State of Michigan, have invented a certain new, original, and ornamental Design for a Therapeutic Lamp, of which the following is a specification, reference being had therein to the accompanying drawings, forming a part thereof, wherein

Figure 1 is a perspective view of a therapeutic lamp showing our new design; and

Figure 2 is a side elevational view thereof.

The dotted line showing in the drawing figures is for illustrative purposes only.

We claim:

The ornamental design for a therapeutic lamp, substantially as shown and described.

ALBERT SIMON.
LAWRENCE RELLINGER.
